UNITED STATES PATENT OFFICE.

FRANCIS D. SWADER, OF NEAR BEARDEN, OKLAHOMA.

MERRY-GO-ROUND.

Application filed July 6, 1928. Serial No. 290,820.

The present invention relates to improvements in roundabouts and has reference more particularly to a merry-go-round that is manually operated by the occupants of the same.

One of the important objects of the present invention is to provide a merry-go-round for children that will afford great amusement as well as exercise to a group of children occupying the seats.

A further object is to provide a merry-go-round of the above mentioned character which is simple in construction, inexpensive, strong and durable and further well adapted to the purpose for which it is designed.

Other objects and advantages will become apparent during the course of the following description.

In the accompanying drawings, forming a part of this specification, and in which like numerals indicate like parts throughout the same:

Figure 1 is a top plan view of the merry-go-round embodying my invention.

Figure 2 is a side elevation thereof, parts being shown in section,

Figure 3 is an enlarged detail of the stationary vertical spindle showing the manner in which the rotatable sleeve is arranged thereon and also disclosing the radial arm 30 that is fixedly secured at its inner end on the upper end of the spindle and

Figure 4 is a detail of one of the seat members.

In the drawings wherein for the purpose of illustration is shown a preferred embodiment of my invention, the numeral 1 designates an upright or post that is anchored at its lower end in the ground and the upper end of this post is externally threaded for receiving thereon an axle unit that includes a socket 2 that is internally threaded for engagement with the upper threaded end of the post or upright 1.

A tapered spindle 3 extends upwardly from the top of this socket member 2 and an annular raceway 4 is formed also in the top of the socket member 2 around the lower end of the spindle as more clearly shown in Figure 3 and the purpose thereof will be presently described.

The upper end of the vertical spindle 3 is threaded as shown at 5 and a substantially square projection 6 is formed on the upper extremity of the spindle as also disclosed in Figure 3 and for a purpose also to be presently described.

A tapered sleeve 7 is mounted for rotation upon the spindle 3 and the lower end of this sleeve is formed with an internal ball race shown at 8 in Figure 3 adapted to cooperate with the race 4 and the ball 9.

The upper end of the sleeve 7 is formed with a ball race shown at 10 which is mounted for movement on the ball bearings 11, and cooperating with the ball race 10 is the threaded ring 12 that is threaded on the upper threaded end 5 of the spindle 3 and a cap 13 is disposed over the ring and is also threaded on the upper end of the spindle as also shown in Figure 3.

The invention further comprehends the provision of a frame that is rotatable about the upright or post 1 as a center and this rotatable frame which is denoted generally by the reference character 14 in addition to including the rotatable sleeve 7, also comprises the radially disposed arms 15 that are arranged in pairs, the inner ends thereof being secured to the lower portion of the sleeve through the medium of the attaching ears 16.

A plurality of rods 17 also extend radially from the sleeve and are connected at their inner ends to the upper portion of the sleeve 7 through the medium of the apertured ears 18 and as is clearly shown in Figure 1, one of such rods is provided for each pair of arms 15.

The outer ends of each pair of radial arms 15 and the adjacent spaced rods are connected to a bracket 19 and the several brackets are interconnected to each other by means of the connecting rod shown at 20 in Figure 1.

A pulley 21 is suspended from the top of each bracket and the purpose will also be presently described. A seat forming unit 95 denoted by the reference character 22 in Figure 4 is suspended from the outer ends of the respective supporting arms 15 by means of the suspension chains 23 and the hanger unit 24.

A crank arm 25 is formed at its inner end with a hub 26, the bore of which is square to accommodate the square projection 6 formed on the upper end of the spindle 3 and a set screw 27 secures the hub of the crank arm on the square projecting end of the spindle. This crank arm 25 extends radially with respect to the spindle and the outer end thereof is provided with the upwardly disposed portion 28 that is of circular form.

Mounted to rotate on and about this out-

wardly projecting portion 28 is the rotary head 29 that is in the form of a disk having a beveled hub. It will be observed that the outer end of the crank arm is arranged off center of movement of the sleeve 7 and furthermore the disk 29 is formed with a series of annular spaced openings whereby the inner ends of the actuating cables 30 may be secured to the rotary head.

10 There are as many cables provided as there are seats, one being associated with each seat and as clearly shown, the outer ends of these cables are trained over the respective pulleys and extend downwardly adjacent the seat 22 15 and an actuating handle 31 is secured to the outer free end of each cable.

The operation of my improved merry-go-round is thought to be readily obvious from the construction shown and described and it 20 will be understood that the speed of rotation of the frame that carries the seats may be controlled by the children occupying seats through the medium of the actuation of the cables 30.

25 A device of the above mentioned character will not only afford amusement but will also provide exercise for the children by bringing into play all of the muscles of the body.

The simplicity of my structure enables the 30 same to be readily and easily assembled or disassembled and will furthermore be strong and durable and at all times positive and efficient in its operation.

35 While I have shown the preferred embodiment of my invention, it is to be understood that various changes in the size, shape and arrangement of parts may be resorted to without departing from the spirit of the invention and the scope of the appended claims.

40 Having thus described my invention, what I claim is:

1. In a merry-go-round, a central fixed post, a vertical spindle fixedly secured on the upper end of the post, a sleeve mounted for rotation 45 on the spindle, arms extending radially from said sleeve, a bracket carried by the outer end of each arm, a seat suspended from each bracket, a pulley carried by each bracket, a crank arm fixedly secured at its inner end on the upper end of the spindle, said arm being disposed radially with respect to the spindle the outer end of the crank arm being disposed 50 upwardly, a head mounted for rotation on the upwardly disposed outer end of said crank arm, a series of actuating cables connected at

their inner ends to said rotatable head extending radially therefrom, said cables being trained over the respective pulleys and hanging downwardly adjacent the respective seats.

2. In a merry-go-round, a central fixed post, 60 a vertical spindle secured on the upper end of the post, a sleeve mounted for rotation on said spindle, arms extending radially from the sleeve and arranged in pairs, a stay rod for each pair of arms, a bracket secured to the 65 outer ends of each pair of arms and its respective stay rod, a pulley carried by each bracket, a seat suspended from each pair of arms at the outer end thereof, connecting rods between the several brackets, a rigidly disposed crank 70 arm fixedly secured at its inner end on the upper end of the spindle, the outer end of the crank arm being directed upwardly, a rotatable disk mounted on the upwardly directed outer end of the crank arm, and a series of 75 cables connected at their inner ends to the rotatable disk, said cables being trained over said pulleys and disposed downwardly adjacent the respective seat.

3. In a merry-go-round, a fixed post, an 80 axle unit removably secured on the upper end of said post, said axle unit including a socket member for receiving the upper end of the post, a spindle extending upwardly from the top of the socket member, the top of said 85 socket member being formed with an annular ball race around the lower portion of the spindle, the upper end of the spindle being threaded, a non-circular projection formed on the upper end of said spindle, a sleeve mounted 90 for rotation on the spindle, the lower end of the sleeve being formed with a ball race, ball bearings arranged in the annular ball race formed in the upper portion of the socket member, a ball bearing unit for association 95 with the upper end of the rotatable sleeve and threaded portion of the spindle, arms extending radially from the sleeve, seats suspended from the outer ends of the arms, a crank arm frictionally secured at its inner end on the 100 non-circular projection formed on the upper end of the spindle, a rotary disk mounted on the outer end of the radially disposed crank arm, an operating means for the merry-go-round controlled by the occupants of the seats, 105 said means having connection with the rotary disk.

In testimony whereof I affix my signature.

FRANCIS D. SWADER.
